C. MONSON.

Holder for Lamps or Gas Burners.

No. 22,664.

Patented Jan. 18, 1859.

Chas. Monson

UNITED STATES PATENT OFFICE.

CHARLES MONSON, OF NEW HAVEN, CONNECTICUT.

HOLDER FOR LAMPS.

Specification of Letters Patent No. 22,664, dated January 18, 1859.

To all whom it may concern:

Be it known that I, CHARLES MONSON, of the city and county of New Haven and State of Connecticut, have invented a new and 5 useful or Improved Counterbalanced Extension-Holder for Lamps or Gas-Burners; and I do hereby declare that the same is fully described and represented in the following specification and the accompanying drawings, of which—

Figure A denotes a perspective view of one form of the same, while Fig. B, is a front elevation of another mode of constructing it.

It is well known that the common method of balancing chandeliers, burners or lamps, which are so hung or suspended as to be capable of being raised or lowered to different altitudes is by means of weights connected to chains carried over or around guide pulleys. Such mode for many reasons is objectionable, and particularly on account of its being attended with more or less liability of breakage of a chain and a consequent fall of the lamp, chandelier, burner, or counterbalance or both. My improvement is intended to overcome the objections to such a mode of counterbalancing a lighting apparatus, and is particularly useful 20 with reference to the extension gas tube or chandelier supporter for which Letters Patent were granted to me in September 1857, an apparatus of such nature being particularly represented in Fig. A of the accompanying drawings, in which figure, as well as in Fig. B, D exhibits a system of crossed and jointed levers usually known by the name of "lazy tongs." In Fig. A the said system of levers is shown as having a system, 25 E, of jointed tubes connected with it substantially as represented in my said patent of September, 1857. Furthermore, the said Fig. A exhibits the extension apparatus as supporting a lighting apparatus or chandelier, F, having two or more burners c, c, the conduit tube, e, of such chandelier or lighting apparatus being suspended from the lower joint, d, of the system of the "lazy tongs". In Fig. B a rod, e, takes the place 30 of a tube and is suspended from the joint, d, of the lazy tongs D, D. This rod, e, may be made to support in a proper manner one or more lamps, G, G, or other articles.

The mode in which I counterbalance an apparatus as above described may be thus

explained: The two levers, i, i, of the upper joint, a, I extend beyond the said joint as shown at z, z, in Figs. A and B, and joint their upper ends respectively to the lower ends of two connecting bars or links, k, k, 60 the upper ends of the said bars, l, being jointed to a slider, l, encompassing and playing on a suspension rod or conducting tube, m. A weight, b, is adapted to the tube, m, in such manner as to be capable of sliding freely thereon and with the slider, l, upon which said weight rests or to which it is to be affixed as circumstances may require. This weight, through its action on the levers, i, i, through the slider, l, and connections, 65 k, k, should be sufficient to counterbalance the downward draft of the lazy tongs or the extension gas tube apparatus or the same and whatever may be suspended therefrom and so that however the lazy tongs may be contracted or extended its parts will be maintained in their positions by such counterbalancing apparatus or means. Furthermore in order to steady the rod or tube, e, 70 the lowermost bars of the lazy tongs may be extended across one another at the joint, d, so as to form two levers, o, o, whose outer ends may be jointed respectively to a slider, p, by connection links, f, g, the slider having the rod or tube, e, passing through it so as to permit the slider to be moved freely in a longitudinal direction on the tube. During expansion of the lazy tongs, the slider will be forced downward on the rod or tube, 75 e, and with the connections, f, g, and levers, 80 o, o, will serve to support the said tube or rod.

It will be evident that instead of a weight, b, a spring might be employed to act on the slider, l, and effect the counterbalancing of 85 the apparatus. Such however would be but a mechanical equivalent for the weight. Furthermore, in case the weight, b, should be attached to the slider, l, the apparatus may be used in reverse, that is to say, it may 90 be inverted in such manner as to cause the weight to depend from the levers, i, i, the rod or tube m, of the weight being fixed to a table or other body. In this way, the weight 95 would pull on the levers, i, i, instead of pushing them, and the apparatus could be extended upward. By such an arrangement of it, it could be made to extend out of a recess, and to fold back or contract therein as 100 occasion might require.

I claim—

1. The mode or means, substantially as hereinbefore specified, of counterbalancing the system of levers or lazy tongs or the 5 same and one or more articles suspended from or supported by them, and this whether the counterbalance weight be applied so as to push or pull on the levers of the lazy tongs as explained.
- 10 2. I also claim the method, substantially as described, of steadying the tube or rod, *e*,

or its equivalent suspended or extending from the lower termination of the system of crossed levers or lazy tongs, viz., by the collar or slide, *p*, the levers, *o*, *o*, and the connections, *f*, *g*, applied to the part, *c*, and the lazy tongs and made to operate essentially as hereinbefore specified. 15

CHARLES MONSON.
